BAND PASS WAVE FILTER

William E. Bradley, Northampton, Pa., assignor to
 Philco Radio and Television Corporation, Philadelphia, Pa., a corporation of Delaware

Application July 24, 1942, Serial No. 452,229

6 Claims. (Cl. 178—44)

1

This invention relates to band pass coupling networks or wave filters, and more particularly to a band pass coupling network having a plurality of substantially non-interacting coupling adjustments.

An important class of band pass wave filters frequently employed in the field of communications is that which utilizes transformers of the double-tuned, over-coupled type. Transformers of this character are commonly employed in the intermediate frequency stages of conventional superheterodyne receivers adapted for use in the reception of amplitude modulated broadcast signals. While these transformer coupled systems have been generally satisfactory in certain limited and conventional applications, including that just referred to, there are other applications in which the transformer coupled system leaves much to be desired. Included in these applications are cascaded wide-band systems wherein it is desired to obtain a particular one of a wide variety of response characteristics simply and reliably. In systems such as these it is difficult, and sometimes impossible, for the designer to obtain desired response and phase characteristics with conventional over-coupled transformers, and this is especially so where the desired response characteristic is asymmetrical. All of these difficulties are aggravated in production where it is important that all tuning operations be capable of quick, simple, and effective adjustment.

By the present invention a compound coupling system is provided which permits of substantially individual control and adjustment of both the high frequency and low frequency halves of the response characteristic. In over-coupled circuits exhibiting two resonant peaks, the invention permits of individual peak adjustments which are substantially independent of each other, and which can be made as readily as the adjustments of single-tuned circuits. Circuits of this character are especially adapted for use in wide-band systems, such as the intermediate frequency stages of television and frequency modulation receivers, and in special applications which may require response characteristics of an asymmetrical character.

It is a principal object of this invention to provide a band pass interstage coupling circuit with which a wide variety of response characteristics may be obtained simply and reliably.

It is another object of the invention to provide an over-coupled interstage coupling circuit in which it is possible to adjust either peak of the two-peak response characteristic independently.

2

and without any sacrifice in the gain of the stage.

It is a further object of the invention to provide a wide-band coupling network capable of giving substantially the maximum gain obtainable in a coupling network between two vacuum tubes.

It is another object of the invention to provide a wide-band coupling network having a novel combination of impedance and admittance coupling.

10 The invention itself, as well as other objects thereof, will be understood from the following description and accompanying drawing, in which:

Fig. 1 is a generalized schematic diagram of the coupling system which comprises the present invention;

Fig. 2 is a schematic diagram of a specific embodiment of the invention; and

15 Figs. 3 and 4 are explanatory diagrams which illustrate the operation and performance of the coupling circuit of the invention.

Reference is now made to the generalized schematic of Fig. 1 in which a double-tuned compound-coupled filter network is illustrated having an impedance coupling element Z_k and an admittance coupling element Y_h . The primary circuit of the network comprises an inductance L_1 tuned by a tuning condenser C_1 and damped by a damping resistor R_1 . The secondary circuit 20 comprises the inductance L_2 tuned by a tuning condenser C_2 and damped by a damping resistor R_2 . The primary and secondary circuits are preferably isochronous, i. e., tuned to the same frequency.

25 While the damping resistors R_1 and R_2 are shown connected in shunt with the tuning condensers C_1 and C_2 respectively, it is to be understood that, alternatively, they may be connected in shunt with the inductances L_1 and L_2 , or if desired the damping resistors may be eliminated entirely, the required dissipation of energy associated with the condensers being achieved, for example, by winding the inductances L_1 and L_2 of a suitable resistance wire.

30 35 Coupling between the primary and secondary circuits is provided, firstly, by means of an impedance Z_k connected between the common junction of L_1 and L_2 on the one hand and the low potential ends of the condensers C_1 and C_2 on the other hand, and secondly by means of an admittance Y_h connected between the high potential terminals of the primary and secondary circuits.

Although it is within the general purview of the invention to make all of the elements of Fig. 1 40 45 50 55 adjustable, it is within the special province of the

invention that at least one, and preferably both, of the coupling devices Y_h and Z_k be adjustable.

If the admittance coupling element Y_h and the impedance coupling element Z_k are properly adjusted, a symmetrical frequency response characteristic can be obtained which is similar to that provided by a conventional double-tuned over-coupled transformer-system, for example, similar to that illustrated by the curve $a-a$ of Fig. 3. The novelty of the present invention resides in the fact that the compound coupling provided by the two coupling elements Y_h and Z_k permits the individual peaks of the double-humped response characteristic to be individually shifted in frequency and varied in height or relative response, each of the adjustments being substantially independent of the other, and having substantially no effect upon the shape of the other peak. If, for example, the element Y_h comprises an adjustable inductive admittance, then adjustment of the imaginary part of the admittance, i. e., the susceptance, will shift the frequency of the high-frequency peak as shown, for example, by the curves $a-b$ and $a-d$ in Fig. 3. On the other hand if the real part (the conductance) of the admittance Y_h is varied, the response or height of the high frequency peak will be affected as is illustrated in Fig. 4 by the curves $e-f$, $e-g$, and $e-h$. Adjustment of the imaginary and the real parts, the reactance and resistance respectively, of the impedance coupling element Z_k will have similar effects upon the shape of the low-frequency response peak.

The invention also contemplates the use of capacitive coupling elements, and if this change is made the coupling element Y_h will control the position and height of the low frequency peak, while the coupling element Z_k will control the position and height of the high frequency response peak. It has been found however that the use of inductive coupling elements provides a higher gain than can be obtained with the use of capacitive coupling elements, and for this reason inductive coupling elements are preferred.

Reference is now made to Fig. 2 in which there is illustrated a specific embodiment of the invention employed as a coupling network between two amplifier tubes V_1 and V_2 . In this particular instance the inductive form of coupling has been chosen for illustration. In Fig. 2 the adjustable inductance L_h and the adjustable resistor R_h comprise the imaginary and real parts, respectively, of the coupling element Y_h of Fig. 1. Similarly the adjustable inductance L_k and the adjustable resistor R_k comprise the imaginary and real parts, respectively, of the coupling element Z_k . In the circuit chosen for illustration, the primary and second tuning capacities, C_1 and C_2 , may be provided in whole, or in part, by the output capacity of the amplifier V_1 and the input capacity of the amplifier V_2 , respectively. Plate voltage for the amplifier V_1 may be supplied from a high potential source $B+$, through a filter comprising a series resistor R_4 and a shunt condenser C_3 , and thence through the damping resistor R_1 to the anode of V_1 . In order to isolate the input grid of the tube V_2 from the high voltage applied to the plate of V_1 a direct current blocking condenser C_4 may be provided as shown. A suitable grid bias, or automatic volume control voltage, may be supplied to the grid circuit of V_2 through a filter comprising the series resistor R_5 and the shunt condenser C_5 as illustrated.

With the form of circuit shown in Fig. 2, adjustment of the inductance L_h effects changes in

the frequency of the high-frequency peak as illustrated in Fig. 3. Moreover the height of the high frequency peak may be varied by adjustment of the shunt damping resistor R_h to produce various response characteristics such as those illustrated in Fig. 4. Adjustments of the inductance L_k and resistor R_k produce similar changes in the position and height of the low frequency peak. Through the adjustment of the elements which comprise the impedance coupling and admittance coupling members, an extremely wide variety of response characteristics may be secured, and a desired response characteristic may readily be duplicated in production by means of tuning adjustments which are individually as simple as those normally made in single-tuned circuits of the simplest character.

In coupling systems designed to have a symmetrical response characteristic, i. e., in which the heights of the two resonant peaks are equal, the real components of Y_h and Z_k , the elements R_h and R_k respectively, may be omitted. In such applications only the input damping resistor R_1 and the output damping resistor R_2 need be employed. In this case the circuit should be designed so that the ratio of R_1 to R_2 is equal to the ratio of C_2 to C_1 . This arrangement will keep the peak heights substantially equal, even when C_1 and C_2 are unequal, for all settings of L_h and L_k .

In the schematic diagram of Fig. 2 adjustable damping resistors have been associated with both L_h and L_k . This has been done for the sake of generality, and such an arrangement may be used in practice where it is necessary frequently to vary the relative heights of the two response peaks. In most practical applications, however, it is preferred to employ only one of the adjustable damping resistors, and then only in conjunction with a predetermined one of the two coupling elements to produce the required asymmetry.

Although the invention is not limited to any particular method of tuning the inductances L_h and L_k , it is preferred that this be accomplished by means of adjustable copper or powdered iron cores in a manner which is well understood in the art.

The damping resistors R_h and R_k may be associated with their respective inductances in any desired manner to produce the required damping effect, but it is preferred that the damping resistor R_h be connected in parallel with the coupling inductance L_h , and that the damping resistor R_k be connected in series with its inductance L_k . Likewise, if desired, the coupling inductances L_h and L_k may be replaced by adjustable condensers of suitable size.

It has been found that the frequency range of the resonant peak controlled by the inductance L_h is larger, ordinarily, than that controlled by the inductance L_k , because the inductance of L_h in practice is usually larger than the inductance L_k . In consequence the inductance L_h tends to resonate with its distributed capacity, making the apparent inductance of this coupling element larger than the actual inductance of the coil. Because of this self resonant action of L_h it is possible to control the high frequency peak over a considerable frequency range. It is not so easy to obtain wide control of the low frequency peak, because the value of L_h is not only much smaller than the other inductances involved, but its leakage inductance is relatively large. This situation can be relieved by the provision of some mutual inductance between L_1 and L_2 so phased as to produce the opposite sign of inductive cou-

pling to that produced by L_k . Under these circumstances L_k can be increased to a larger value, with the result that its tuning range is greatly extended.

The coupling network of the present invention is especially well suited for use in multi-stage amplifier systems, in which a plurality of individual stages (e. g. five or six), each constructed in accordance with the invention, may be connected in cascade. In such a system it is often desirable to "stagger" the tuning of the various stages, i. e., to peak the individual circuits at predetermined different frequencies. For example, a large number of stages, each having characteristics similar to that of the curve $a-a$ of Fig. 3, but each with its characteristic displaced in frequency a predetermined amount, may be connected in cascade to provide a wide-band, substantially flat-top, characteristic having greater overall gain and a more desirable overall phase 10 characteristic than could be obtained by means of an equal number of identically-tuned flat-topped circuits connected in cascade. In other instances it may be desirable to combine amplifiers having characteristics similar to the one designated $e-g$ in Fig. 4 with amplifiers having characteristics of the type designated $e-h$. In all of these multistage applications, the feature of the network which makes it possible to adjust independently either peak of the two-peak response is of great importance. This makes possible simplified production adjustment of the stages, the various trimmers being "peaked" at definite frequencies with a signal generator and output indicator, the correct response characteristic then following automatically.

While the invention has been described with particular reference to a specific embodiment and to a particular mode of operation, it will be understood that the invention is capable of general application and is adapted to other forms of physical expression and is, therefore, not to be limited to the specific disclosure, but only to the scope of the appended claims.

I claim:

1. A band pass coupling network comprising: a primary circuit including a primary winding and a primary tuning capacitance; a secondary circuit including a secondary winding and a secondary tuning capacitance; and an impedance coupling element connected in a circuit which is common to both said windings, said impedance coupling element having an adjustable imaginary component; an admittance coupling element connected between a high potential point on said primary winding and a high potential point on said secondary winding, said admittance coupling element having an adjustable imaginary component; said coupling elements being characterized in that they are non-resonant, and of such magnitude that an over-coupled condition is effected between said primary and second-

ary circuits, the degree of over-coupling being such that a double-peaked frequency-response characteristic is achieved; one of said coupling elements including a real component, the magnitude of which determines the height of one of said peaks without substantial effect upon the height of the other of said peaks.

5 2. A band pass coupling network, as claimed in claim 1, characterized further in that, in addition to the coupling provided between said primary and secondary circuits, said primary and secondary windings are coupled by means including mutual inductance, said mutual inductance being of such sign as to oppose the coupling effect of said impedance coupling element.

10 3. A band pass coupling network comprising: a primary circuit including a primary winding and a primary tuning capacitance; a secondary circuit including a secondary winding and a secondary tuning capacitance; a first variable-inductance coupling coil; means for connecting said primary winding, said primary tuning capacitance and said coupling coil in a closed series circuit; means for connecting said secondary winding, said secondary tuning condenser and said coupling coil in a second closed series circuit; and a second variable-inductance coupling coil connected between predetermined high potential points on said primary and secondary windings; the inductance of said coupling coils being of a magnitude such that an over-coupled condition is effected between said primary and secondary circuits, the degree of over-coupling being such that a double-peaked frequency-response characteristic is achieved, the position of said peaks along the frequency axis being substantially independent functions of the adjustment of said coupling coils.

15 4. A band pass coupling network as claimed in claim 3, characterized in the provision of resistive means in damping relation to at least one of said coupling coils, the resistance of which determines the relative height of said peaks.

20 5. A band pass coupling network as claimed in claim 3, characterized in that, in addition to the coupling provided between said primary and secondary circuits, said primary and secondary windings are coupled by means including mutual inductance, said mutual inductance being of such 25 sign as to oppose the coupling effect of said first variable-inductance coupling coil, and thus to permit the use of a larger-than-normal first coupling inductance, thereby to increase the frequency range obtainable through adjustment of said coupling coil.

25 6. A band pass coupling network as claimed in claim 3, characterized in the provision of resistive means for damping said primary circuit, and independent resistive means for damping said secondary circuit.
